UNITED STATES PATENT OFFICE

102,284

DESIGN FOR A DISPLAY CASE

Luther E. McCoy, Portland, Oreg.

Application April 13, 1936, Serial No. 62,103

Term of patent 7 years

To all whom it may concern:

Be it known that I, Luther E. McCoy, a citizen of the United States residing at Portland, in the county of Multnomah and State of Oregon, have invented a new, original, and ornamental Design for Display Cases, of which the following is a specification, reference being had to the accompanying drawing, forming a part thereof.

In the drawing, Fig. I is a perspective view of the display case, showing my new design; and

Fig. II is a fragmentary detail sectional view

of a corner of the case, on an enlarged scale, taken at line II—II of Fig. I.

The characteristic feature of the design resides in the curvilinear contact surface between the movable glassed frame and the body of the case, as shown.

I claim,—

The ornamental design for a display case substantially as shown and described.

LUTHER E. McCOY.
